UNITED STATES PATENT OFFICE.

KARL M. FETZER, OF RUTHERFORD, AND NORMAN A. NEWELL, OF LYNDHURST, NEW JERSEY, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

Application filed October 10, 1924. Serial No. 742,749.

This invention relates to improvements in telephone exchange systems, and especially to those systems employing what is known as straightforward trunking between switchboards or exchanges.

In such systems, an "A" or outward operator receives an originating call and connects it to a "B" or inward operator who may be located in the same or in a distant exchange.

An object of the invention is to improve the operating efficiency of systems of this character.

In the patent to Fetzer No. 1,578,651 issued March 30, 1926, there is disclosed a system wherein the signaling between A and B operators is controlled over a common signaling circuit and in which the B operator's telephone set is automatically connected in a predetermined sequential order to the calling trunks.

In the system described, a line lamp is provided at the B operator's position for each incoming trunk and when one of the trunks is seized at the A operator's position, for the purpose of initiating a call, a signal is transmitted over the common signaling circuit to cause the lamp associated with the seized trunk to light and to connect the B operator's telephone set to the trunk. When the B operator extends the trunk by plugging it into a subscriber's line, or another trunk, the lamp is extinguished and the operator's telephone is disconnected. When the A operator releases the trunk, another signal is transmitted over the common circuit to cause the lamp to relight as a disconnect signal whereupon, in the ordinary course of operation, the B operator will remove the trunk plug from the called line, thus extinguishing the lamp and restoring the circuit to normal.

However, in case the A operator, after releasing the trunk, which causes a disconnect signal to be displayed at the B operator's position, should again seize the same trunk for the purpose of initiating a second call before the B operator has disconnected the trunk from the first called line, a third signal is transmitted over the common circuit which maintains the previously lighted disconnect signal, which now acts as a re-connect signal, and which also causes the op-

erator's telephone set, to be connected to the trunk in the regular sequential order, 55 whereupon the signal is caused to flash as before.

A feature of this invention, therefore, resides in the provision of means, in a system as before described, whereby a trunk disconnect signal at an inward or B operator's position is maintained as a connect signal upon an originating or A operator reseizing the trunk before it has been disconnected at the B position.

The invention is illustrated in the accompanying drawings wherein:

Fig. 1 shows the apparatus used in conjunction with the common signaling circuit in connection with an "A" operator's position.

Fig. 2 shows the apparatus at the "A" operator's position including a trunk line extending to the "B" operator's position and the timing apparatus associated with the 75 cord circuits for allowing the "A" operator to change cords without sending a disconnect signal to the "B" operator.

Fig. 3 shows the "B" operator's position with a trunk circuit and controlling apparatus operating in conjunction with the common signaling circuit.

Fig. 4 shows the operator's telephone sets and call sequence circuits for two "B" operator's positions and the auxiliary apparatus therefor.

Fig. 5 shows a portion of the apparatus of the common signaling circuit which operates with the apparatus of Fig. 1.

Fig. 6 shows the switching mechanism and apparatus associated with the common signaling circuit located at an "A" operator's position.

Fig. 7 shows the switching mechanism and apparatus associated with the common signaling circuit located at the "B" operator's position which operates in synchronism with the apparatus at the "A" operator's position.

General method of operation.

The straightforward trunk line circuits are arranged to give complete switchhook supervision to the outward operator. The circuits are arranged to start machine ringing when the connection is established and to

enable the outward operator to rering in order to recall a subscriber.

The trunk circuits disclosed herein are arranged to be used with a distributor signaling system, but the use of other signaling arrangements may be readily provided for.

The trunk lines terminate in the outward board in multiple jacks equipped with visual 10 busy signals and at the inward board in a single cord and plug with associated lamp signal and team key.

The outward operator originating a call after securing connection with the calling 15 subscriber by means of the answering end of a cord circuit places the calling plug of the cord circuit into the trunk jack of an idle trunk line. This operation causes the busy signals to be displayed and lights the 20 signal lamp at the inward end of the trunk and also connects a tone signal to the trunk line, notifying the outward operator that the connection is being extended to the inward operator's telephone set.

25 At the inward end of the trunk circuit, the inward operator's telephone set is automatically connected in succession to trunk lines on which calls are waiting. When the operator's telephone set is connected, the tone 30 signal is disconnected from the trunk line and the outward operator then immediately passes the call. The inward operator completes the connection in the usual manner by placing the trunk plug into the jack of the 35 subscriber's line. The inward operator's telephone set is disconnected from the trunk line either when the trunk plug is placed into the line jack of the called subscriber or by the operation of a release key common 40 to the position.

The inward operator at a position adjacent to one in which trunk lines terminate may answer on these trunk lines by operating the team key. The purpose of this feature 45 is to allow team work among the inward operators. The adjacent operator's telephone set is released from a toll line in the same manner as that of the home operator.

50 The trunk lines are available for other connections as soon as released by the outward operator if the called subscriber's receiver is on the switchhook. Provision is made for a delay of 2½ seconds before the disconnect signal is transmitted and the 55 visual busy signal released, if the outward operator should disconnect while the receiver of the called subscriber is off the switchhook. The reason for this delay is to permit the outward operator to change cord circuits if necessary, for example in case the first cord circuits are defective. The change if made within 2½ seconds is effected without giving a disconnect signal to the inward operator.

60 After the outward operator secures from

the calling subscriber the number of the wanted line, she places the calling plug P into an idle trunk jack J. This completes the circuit of relay 3 as follows: ground, battery, winding of relay 2, 100, winding of 70 relay 1, 101, P, J, 102, winding of relay 3 to ground.

The operation of relay 3 completes the circuit of relay 4 as follows: ground, contacts of relay 3, 105, contacts of relay 5, 106, 75 contacts of relay 13, 107, winding of relay 4, 108, contacts of relay 8, battery to ground.

Relay 4 operates and closes the circuit of 80 relay 5 as follows: ground, battery, inner left contacts of relay 4, 109, winding of relay 5, 110, contacts of relay 13, to ground. When relay 4 operates it also connects ground to conductor 121 extending to the signal sequence circuit (Fig. 1) and causes this circuit to function to cause the transmission of a current pulse over conductor 600 (Fig. 6) and 700 (Fig. 7) to operate relay 701 at the distant end of the trunk line as will be described later.

90 The operation of relay 4 connects battery to the winding of the busy signal 16 indicating that its associated multiple jacks are busy. These signals are held operated after relay 4 releases as relay 5 also connects battery to the winding of the busy signals. 95 The operation of relay 4 also closes the circuit of relay 7 as follows: ground, battery, left inner contacts of relay 4, winding of relay 7, 127, contacts of relay 6 to ground. The operation of relay 5 opens the circuit 100 which resulted in the operation of relay 4, but this latter relay remains locked to ground under control of relay 8 through its own contact.

105 Relay 5 is locked to battery through one of its own contacts and can only be released by the operation of relay 13. The operation of relay 7 disconnects the grounded right hand winding of relay 10 from conductor 125 thereby removing the short circuit 110 around the right hand winding of relay 6.

115 Returning now to the operation of the signal sequence circuit, when ground was connected to the conductor 121, it caused the operation of relay 17 (Fig. 1), a circuit for which can be traced from ground, outer right alternate contacts of relay 4, conductor 121, winding of relay 17, normal contacts of relays 18 and 19, and the contacts of any other relays between relays 18 and 19, as 120 shown by the broken line to battery and ground.

125 Relay 17 in operating connects ground at its alternate contacts to energize relays 30 and 31 in an obvious circuit. Relay 31 in operating causes the energization of relays 501 and 502 (Fig. 5) in the following circuit:

130 Ground, outer right alternate contacts of relay 4, conductor 121, left alternate con-

tacts of relay 31, conductor 32, right hand winding of relay 501, conductor 503 and winding of relay 502 to battery.

Relay 502 in operating grounds the ST 5 lead extending through relay 601 to battery, which relay energizes and in closing its alternate contacts completes a circuit for the operation of relay 602, which can be traced from ground on the ST lead over contacts 10 of relays 601 and 603, through winding of relay 602 to battery.

Relay 602 in closing its contacts completes the circuit for the start magnet 604, which can be traced from battery through the 15 winding of magnet 604, alternate contacts of relay 602, segment 605 of the transmitter distributor TRANS, brush arm 606 and the grounded inner segment of the distributor.

Magnet 604 in attracting its armature releases brush arm 606, which starts revolving in a clockwise direction. When the brush arm starts to revolve the outer brushes break contact with segment 611, thereby opening the normally closed circuit of relay 25 610, the energizing circuit for which can be traced from battery over segment 609 of the transmitting distributor, brush arm 606 and its brushes, segment 611, lead 613, and the winding of relay 610 to ground.

30 When relay 610 deenergized, its armature opened its alternate or front contacts and caused relay 701 (Fig. 7) at the distant end of the line to release, which relay is normally operated due to the normally 35 operated condition of relay 610.

Relay 701 in releasing connects ground at its alternate contacts over lead 702 to segment 703 of the receiving distributor REC, thereby causing release magnet 704 to attract its armature and release brush arm 40 705, which at once starts to revolve in a clockwise direction in substantial synchronism with the transmitting distributor.

When the brush arm 606 reaches segment 45 607 it connects battery standing on segment 609 to lead 608, thereby causing the reenergization of relay 610 in the following circuit: battery, segment 609, brush arm 606, segment 607, lead 608, contacts of relay 501, leads 504 and 505 and the winding of relay 610 to ground.

Relay 610 in operating reconnects battery at its alternate contacts to lead 600, thereby causing relay 701 at the distant end to operate, which connects ground over lead 55 706 to segment 707 of the receiving distributor. As before mentioned, the transmitting and receiving distributors rotate in substantial synchronism and, therefore, during the 60 period the brush arm 606 of the transmitter has its brushes in contact with segment 607, brush arm 705 of the receiving distributor will bring its brushes into contact with segment 708, thereby completing a circuit 65 for the operation of relay 709, which can

be traced from battery 710, winding of relay 709, segment 708, outer brushes of brush arm 705, segment 707, conductor 706 and normal contacts of relay 701 to ground.

When relay 709 operates, it locks itself by 70 means of its right winding and inner armature contacts to ground on segment 711, over segment 712 and the inner brushes of brush arm 705, which locking circuit will be maintained closed until the brush arm 705 leaves 75 segment 711 near the completion of the revolution.

When relay 709 operated, it connected ground at its outer armature contacts to conductor 713, thereby causing the operation 80 of relays 714, 715, 716 and 717 in an obvious circuit.

Relay 714 in operating prepares a circuit for the operation of relay 39 associated with the inner end of the conductor (Fig. 3), 85 which circuit will be closed when the brush arm of the receiving distributor bridges segments 718 and 719. The circuit thus completed can be traced from negative battery over conductor 720, normal contacts of relay 90 721, segment 718, outer brushes of brush arm 705, segment 719, outer normal contacts of relay 722, lower normal contacts of relay 723, lower normal contacts of relay 724, 95 lower alternate contacts of relay 714, upper normal contacts of relay 726, conductor 725 and left hand winding of relay 39 to ground, which relay in operating locks itself at its right hand alternate contacts to battery.

It should be noted that the windings of 100 relay 39 are so connected that the negative locking battery aids the negative battery supplied through the left hand winding whereby the relay remains operated after the operating pulse ceases, whereas a positive operating pulse would have momentarily operated the relay but it could not have locked as it would have opposed the negative locking battery.

As none of the other chain relays (Fig. 5) 110 were operated by the seizure of the trunk line, shown in Fig. 2, none of the other four outer segments 614, 615, 616 and 617 of the transmitting distributor will affect relay 610 and, therefore, its armatures will retract as soon as the outer brushes of brush arm 606 leave segment 607 and will remain in its retracted position until the brushes contact with segment 611, at which time relay 610 will again energize to cause the re- 115 energization of relay 701, which as before mentioned, is the normal condition of these relays.

When the inner brushes of brush arm 606 made contact with segment 618, an obvious 120 energizing circuit was completed for relay 603.

When relay 603 closed its left alternate contact it prepared an energizing circuit for relay 619 which can be traced from battery, 130

through the winding of relay 603, left alternate contacts of relay 603, winding of relay 619 and left alternate contact of relay 601 to ground on the ST lead.

5 Relay 619 did not operate in this circuit, however, as its winding was shunted by ground on segment 618 of the distributor, as previously mentioned. When the brush arm 606, however, in completing its revolution moved off segment 618, this short circuit was removed from relay 619, and, therefore, this relay operated in the circuit previously traced.

15 The operation of relay 619 completes an energizing circuit for relay 8 (Fig. 2), which can be traced from battery, winding of relay 8, conductor 122, right hand alternate contacts of relay 31, (Fig. 1), conductor 33, alternate contacts of relay 619, conductor 620, alternate contacts of relay 601 to ground on the ST lead, which is supplied at the alternate contacts of relay 502, (Fig. 5).

25 The operation of relay 8 opens at its normal contacts the holding circuit for relay 4, which relay releases and removes ground at its outer right alternate contacts from lead 121, thereby causing the deenergization of relays 17, 501, 502, 30 and 31. Relay 39 35 502 in releasing removes the ground from the ST lead thereby causing the release of relays 601, 602, 603 and 619. The release of relay 602 opens the circuit for the start magnet 604, which therefore, releases its 45 armature, which takes up a position to stop the brush arm 606, when it has completed its revolution. All relays associated with the transmitting distributor are now in normal position and in readiness to transmit another signal.

40 The release of relay 4 (Fig. 1), which removes the ground from conductor 121, prevents further transmission of signals until further changes occur at the outward end 45 of the trunk circuit.

The operation of relay 39 (Fig. 3) at the inward end of the trunk completes the circuit of relay 60 as follows: ground, battery, contacts of relay 39, contacts of relay 40, 55 179, winding of relay 60, contacts of relay 56 to ground.

50 The operation of relay 39 completes the circuit of the signal lamp Q as follows: ground, battery, contacts of relay 39, 170, 65 contacts of relay 46, 172, contacts of relay 47, 174, contacts of relay 43, 176, contacts of relay 47, 177, contacts of relay 46, 178, lamp Q to ground. The lighting of this 70 lamp notifies the inward operator of the call.

65 The operation of relay 39 also completes the circuit of relay 41 as follows: ground, battery, contacts of relay 39, 170, contacts of relay 46, 172, 173, contacts of relay 47, 174, contacts of relay 43, 175, winding of

70 relay 41 to ground. The operation of relay 41 connects tone to the tip and ring conductors 134 and 135 of the trunk, thus indicating to the outward operator that the signal has been transmitted to the inward operator's position.

The operation of relay 39 also completes the circuit of relay 42 as follows: ground, battery, contacts of relay 46, 172, 39, 170, contacts of relay 173, contacts of relay 47, 174, right hand winding of relay 42 to ground. The operation of relay 42 connects ground from relay 70 (Fig. 4) and conductor 190 over conductor 189 to the call sequence circuit which includes relay 72 thereby causing the connection of the operator's telephone set to the selected trunk. The operation of relay 42 also transfers one terminal of its left hand winding from ground to conductor 196. The reason for this connection will be later explained.

80 The operation of relay 42 as above mentioned, closes the circuit of relay 72 as follows: ground, contacts of relay 70, 190, contacts of relay 42, 189, winding of relay 72, 90 contacts of relay 76, 184, contacts of relay 75, 185, battery to ground.

95 When there are no calls awaiting on other trunks ground is connected to relay 43 as follows: ground, contacts of relay 71, alternate contacts of relay 72, 182, winding of relay 43 to battery. The operation of relay 43 opens the circuit of relay 41, thereby releasing it, which disconnects the tone signal from the tip and ring conductors notifying the outward operator that the inward operator is connected to the trunk and is in position to receive the order relay 41 at the same time it connects the tip and ring conductors 134, 135 of the trunk to conductors 136 and 105 137.

100 The operation of relay 43 also connects the tip and ring of the No. 1 operator's telephone set to conductors 136 and 137 thus completing a connection with the trunk so 110 the inward operator may converse with the outward operator.

115 Relay 42 is slow in operating while relay 41 is slow in releasing. This combination insures that the tone signal is connected to the toll trunk for a sufficient length of time to give the full signals to the outward operator.

120 The operation of relay 43 also disconnects continuous battery from the lamp Q and connects interrupted battery to the lamp as follows: ground, battery, contacts of interrupter relay 83, 253, 201, contacts of relay 43, 176, contacts of relay 47, 177, contacts of relay 46, 178, lamp Q to ground.

125 This interrupted battery current causes the lamp to flash at a certain (busy back) frequency indicating to the inward operator to which trunk circuit her telephone set is connected.

5 The operation of relay 43 also connects battery to the left hand winding of relay 42 as follows: ground, battery, contacts of relay 39, 170, contacts of relay 46, 172, 173, contacts of relay 47, 174, contacts of relay 43, winding of relay 42. The reason for this connection will be explained in the description of the operation of the position release key.

10 When the "B" or inward operator receives the order from the "A" or outward operator she places the plug P' of the trunk into the jack J' of the wanted line, causing the operation of relay 44. The operation of relay 15 44 completes the circuit of relay 46 as follows: ground, contacts of relay 44, 191, 46, 192, contacts of relay 63, battery to ground. The operation of relay 46 opens the circuit of the lamp Q, closes the tip conductor of 20 the trunk and disconnects battery from the winding of relay 42. The release of relay 42 disconnects ground from conductor 189 extending to the call sequence circuit, Fig. 4, and this in turn disconnects ground from 25 conductor 182 causing the release of relay 43. The release of relay 43 disconnects the inward operator's telephone set from the trunk.

When there are several calls waiting on 30 trunk lines terminating in one position and the operator adjacent to this position is idle she may answer one of the waiting calls by operating the team key associated with the trunk line. The team key individual to each 35 trunk is shown at X. The operation of this key completes the circuit of relay 47 as follows: ground, contacts of X, winding of relay 47, 172, contacts of relay 46, 170, contacts of relay 39, battery to ground.

40 The circuit of relay 48 is completed in parallel to that of relay 47 over the path just traced. When relays 47 and 48 are operated they remain locked to ground through contacts of relay 48 to conductor 211. This 45 ground is furnished through release key 700' of the adjacent operator's position.

The operation of relay 48 also connects the tip and ring and busy test lead of the adjacent or No. 2 operator's telephone to the 50 trunk. The operation of relay 47 connects ground to conductor 257 extending through contacts of relay 70 and over conductor 258 to the call sequence circuit of the adjacent or No. 2 operator's position operating relay 55 71'. Ground being connected in this manner prevents the No. 2 operator's telephone set being automatically connected to a trunk line at her own position while she is working upon the trunk of the adjacent or No. 1 60 position, as the operation of relay 71' removes ground from the series contacts of relays corresponding to 72, 73, 74, etc., of the No. 1 position. The operation of relay 71' completes the circuit of relay 84 as follows: 65 ground, battery, contacts of 71', 202, wind-

ing of relay 84, interrupter Z to ground. Relay 84 is intermittently operated by interrupter Z at a different (peremptory) rate than relay 83 and causes the lamp circuit Q to be interrupted over the following path: 70 ground, battery, contacts of relay 84, 252, contacts of relay 70, 251, contacts of relay 47, 177, contacts of relay 46, 178, lamp Q to ground.

The flashing of lamp Q at this peremptory 75 rate indicates to the No. 1 operator that the call has been answered by another operator.

The operation of relay 47 also disconnects battery from the winding of relay 41 and the auxiliary signal circuit and from 80 the winding of relay 42. The release of relay 41 disconnects the tone signal from the trunk line and the release of relay 42 disconnects ground from conductor 189 extending to the call sequence circuit.

The adjacent operator completes the connection in the usual manner and connects the trunk with a subscriber's line, thereby operating relay 44 in the manner previously 90 described.

The operation of relay 46 closes the tip side of the trunk circuit, extinguishes the signal lamp and disconnects battery from the windings of relays 47 and 48 causing 95 their release. The release of these relays disconnects the inward operator's telephone set at the adjacent position from the trunk line.

When the connection is completed to the line of the called subscriber by any inward operator the sleeve relay 44 connects ground to operate relays 49 and 50. The circuit of relay 49 is completed as follows: ground, contacts of sleeve relay 44, 220, contacts of relay 62, 228, contacts of relay 61, 229, contacts of relay 55, 231, contacts of relay 50, 232, contacts of relay 49, winding of relay 49, 233, contacts of relay 55, battery to ground. The circuit of relay 50 is completed over the same path as relay 49 except that its winding is connected directly to 105 battery instead of through the contacts of relay 55.

Relay 50 is slightly slow in operation and does not open the circuit extending to relay 49 until the latter relay has had time to operate and lock to ground through its own contact.

The operation of relay 49 connects ground to conductor 222 which results in the transmitter distributor 728 sending over conductor 727 signal impulses to the outward end of the trunk to set up a condition in the signal receiving circuit 621 of Fig. 6 in exactly the same manner as that previously described in connection with the initiation of the trunk connection. It will be assumed that the condition set up in the signal receiving circuit 621 of Fig. 6 causes negative 120 volt battery to be momentarily connected to conductor 125 extending through 125 130

the right hand winding of relay 6 (Fig. 2) to ground thus causing this relay to operate when the receiving distributor 622 bridges its segments corresponding to 717, 179 of the distributor shown in detail in Fig. 7. Relay 6 in operating locks through its left hand winding and left armature contact to battery at the inner left alternate contact of relay 5 which relay it will be recalled was operated and locked under control of relay 13 at the time the trunk was seized.

Relay 3 is of a sufficiently high resistance so that relay 1 did not operate in series with it, and relay 2, when the plug was inserted in jack J. When relay 6 operates however, resistance A is connected in shunt with relay 3 thereby causing a sufficient change in the resistance of the circuit of relay 1 to enable it to operate thereby lighting lamp L to indicate to the "A" operator that the connection has been completed to the line of the called subscriber but that all the receivers on the line are on their hooks.

Relay 6 in operating deenergizes slow-to-release relay 7 but this relay, due to its slow character, does not close its right normal contacts to connect relay 10 to lead 125 until after the 120 volt negative pulse has ceased. When relay 7 however is fully released relay 10 is connected to lead 125 and is in readiness to respond to any further impulses of current connected thereto in the signal receiving circuit 621.

Returning to the inward end of the trunk: After relay 50 operates, it is held operated by ground supplied through contacts of relay 44, until relay 51 has operated, and will only be released by the operation of supervisory relay 62. The operation of relay 50 completes the circuit of relay 52 as follows: ground, contacts of relay 44, 220, contacts of relay 52, 228, contacts of relay 61, 229, contacts of relay 55, 231, contacts of relay 50, winding of relay 52, battery to ground.

Relay 52, in operating, connects a slow acting relay 59 to the alternate contacts of relay 62. Relay 59 does not operate at this time, however, since relay 62 is not yet operated.

The functions controlled by the operation of relays 52 and 49 will be later described in connection with the flashing system.

The operation of relay 49 completes the circuit of relay 53 as follows: ground, contacts of relay 49, 216, contacts of relay 54, 215, winding of relay 53, contacts of relay 39, battery to ground.

So long as relay 49 remains operated operation of relay 53 has no effect upon the circuit but as soon as relay 49 releases a short circuit is removed from the winding of relay 54 which then operates in series with relay 53. Relays 54 and 53 are locked to ground through a back contact of relay 61, the purpose of which will be described later.

When the signal sent over the distributor signaling circuit has been transmitted to the "A" or outward position, where it operates relay 6 etc., as previously described, a momentary ground connection is made with conductor 224 when the transmitting distributor 728 completes its revolution in the same manner that ground was connected to conductor 33 to operate relay 8 as previously described. This ground on conductor 224 operates relay 55 for a short interval of time. The operation of relay 55 will release relay 49 and leave it in a position to transmit another signal to the signal storing circuit.

The release of relay 49 causes the operation of relay 54 in the manner previously described. The operation of relay 54 completes the following circuit: ground, contacts of relay 52, 204, contacts of relay 54, 203, contacts of relay 60, 205, left hand winding of relay 56, 206, contacts of relay 57, 207, "pick up" interrupter 500 to battery. Relay 56 locks up through its second winding to battery through contacts of relays 39 and 57.

The operation of relay 56 prepares a circuit for operating relay 57 when relay 52 is released and also connects the winding of relay 58 to ground through interrupter 600. The operation of relay 56 also opens the circuit of relay 60 causing it to release, the purpose of which will be described later.

The circuit of relay 58 is completed as follows: ground, interrupter 600, contacts of relay 51, 226, contacts of relay 56, 227, winding of relay 58, battery to ground. The operation of relay 58 connects ringing current to the tip and ring conductors of the outgoing end of the trunk to the called subscriber's line.

Ringing current will be applied to the subscriber's line in two second intervals, such intervals being regulated by the commutator of interrupter 600.

When the called party removes his receiver the supervisory relay 62 operates. The operation of this relay opens the circuit of relay 50 which in turn opens the circuit of relay 52. Relay 59 operates momentarily but has no effect upon the circuit. The release of relay 52 causes the operation of relay 57 by completing ground to the following path: ground, contacts of relay 44, 220, contacts of relay 62, 219 contacts of relay 52, contacts of relay 54, contacts of relay 56, left hand winding of relay 57, contacts of relay 39, battery to ground. Relay 57 locks through its right hand winding to ground through the back contact of relay 40, and its operation causes the release of relay 56. The release of relay 56 disconnects relay 58 from the ringing interrupter and opens the operating circuit for relay 57. The release of relay 56 causes relay 60 to become operated again.

The release of relay 52 connects ground to relay 61 as follows: ground, contacts of relay 44, 220, contacts of relay 62, 219, contacts of relay 52, contacts of relay 54, 211, 5 contacts of relay 29, 210, winding of relay 61, 234, contacts of relay 55, battery to ground.

The operation of relay 61 connects ground to conductors 222 and 223 extending to the 10 signal control circuit (Fig. 7) and establishes a condition which results in the transmitting distributor 728 sending over conductor 727 two current pulses which cause the receiving distributor 622 and the signal 15 receiving circuit 621 to connect a momentary pulse of positive polarity 120 volt current to conductor 125 which, due to the connection of the windings of relay 6, causes this relay to release. The reason for this is 20 that the locking current flowing in the left winding of relay 6 is of negative polarity and as the connection of the right hand winding to conductor 125 is such that a negative pulse incoming thereover will aid the locking 25 circuit, then a positive pulse coming in over the conductor 125 will oppose the effect of locking circuit and cause the relay to release.

The release of relay 6 removes the shunt from relay 3 and thereby increases the resistance in the circuit of relay 1 to such a point that it will not hold operated. The release of relay 1 opens the circuit of lamp L which becomes dark and signifies to the "A" operator that the called subscriber has 35 responded.

The operation of relay 61 also releases relays 53 and 54.

When the receiver of the called subscriber is removed and the signal indicating that 40 fact has been transmitted over the distributor signaling circuit, a short impulse of ground is applied to conductor 224 at the transmitting distributor circuit, in the same manner as previously described in connection 45 with the outward end of the circuit, which operates relay 55 momentarily. The operation of relay 55 opens the circuit of relay 61 and leaves the circuit in a condition so that other signals may be transmitted to 50 the signal storing circuit.

Should the called subscriber replace the receiver on the switchhook before the connection is taken down, the outward operator may recall him if desired by ringing on 55 the circuit in the usual manner.

When the outward operator re-rings, the ringing current flowing over conductors 130 and 131 passes through the winding of relay 11 which is in series with condenser R and 60 retardation coil C.

The ringing current operates relay 11 which in turn completes the circuit of relay 12 as follows: ground, contacts of relay 11, 123, winding of relay 12, 124, contacts of relay 4, battery to ground.

When relay 12 operates it locks to ground through contacts of relay 3. When the operator ceases ringing, relay 11 releases and closes the circuit of relay 4 as follows: 70 ground, contacts of relay 11, contacts of relay 12, contacts of relay 13, 107, winding of relay 4, 108, contacts of relay 8, battery to ground. Relay 4 locks up again over its right hand contacts to battery at relay 8.

The operation of relay 4 releases relay 12 75 by disconnecting battery from its winding, and also connects ground over conductor 121 to the signal storing circuit.

In order to make the most efficient use of the distributor shown in Figs. 6 and 7, the 80 same signal combination is used for ringing as was used to light the lamp Q when the call was initiated, therefore the re-ring impulse is received at the inward end of the trunk as a second impulse of negative 120 85 volt battery current over conductor 125. When this second impulse of negative 120 volt current is transmitted over conductor 225 relays 39 and 60 are already operated 90 which permits the operation of relay 40 90 over the following path: ground, contacts of relay 60, 181, winding of relay 40, contacts of relay 40, contacts of relay 39, 95 battery to ground.

The operation of relay 40 opens the circuit of and causes the release of relay 57 and completes the circuit of relay 56 as follows: 100 ground, contacts of relay 40, 203, contacts of relay 60, 205, winding of relay 56, 206, contacts of relay 57, 207, interrupter 500 to ground.

The operation of relay 56 connects the ringing control lead to the winding of relay 58 causing it to operate as previously described. The operation of relay 56 also 105 opens the circuit of and causes the release of relay 60, which in turn opens the circuit of and causes the release of relay 40.

The operation of relay 58 connects ringing 110 current to the trunk and if the called subscriber's receiver is on the switchhook, the ringing continues until the receiver is removed from the hook or until the connection is released.

If the called subscriber's receiver is off the switchhook the operation of relay 58 will release relay 62 which will allow relays 49 and 50 to be operated from ground through the contacts of relay 44 as previously described.

The operation of relay 49 will connect ground to conductor 222 to transmit a signal to the outward position where it will light lamp L for a short period. This signal is transmitted in exactly the same manner as 125 previously described. However, when relay 58 releases on the first break of interrupter 600 and relay 62 operates relay 61 operates to transmit a signal to the outward position which extinguishes lamp L thus indicating 130

that the receiver is off the hook. The transmission of this signal is the same as has been previously described. The operation of relay 62 causes the operation of relay 57 by closing the following path: ground, contacts of relay 44, 220, contacts of relay 62, 219, contacts of relay 52, contacts of relay 54, 211, contacts of relay 56, 212, left hand winding of relay 57, contacts of relay 39, battery to ground. The operation of relay 57 opens the circuit of relay 56 which upon restoring disconnects the ringing control conductor from the winding of relay 58 thus causing ringing current to be discontinued.

15 When the ringing signal which was established in the signal storing circuit by the ground applied to conductor 121 has been transmitted over the distributor signaling circuit, an impulse of ground is furnished 20 from the signal circuit to the outward trunk circuit over conductor 122 as has been previously described, resulting in the operation of relay 8, and in turn the release of relay 4. The release of relay 4 removes ground from 25 conductor 121 and prevents any more signals being transmitted to the signal storing circuit until a further change has been made in the outward trunk circuit.

When the called subscriber flashes, that is 30 moves his switchhook up and down to attract the "A" operator's attention, the first downward movement releases relay 62. Relay 62 in releasing closes at its back contact a parallel circuit for the operation of relays 35 50 and 49 which can be traced from ground at the inner alternate contact of relay 44, conductor 220, contact of relay 62, 228, outer normal contacts of relay 61, 229, right normal contacts of relay 55, 231, then the circuit branches to the right through the right hand contacts and winding of relay 50 to battery, and to the left through the left hand normal contact of relay 50 and the right hand normal contact, the winding of relay 45 49 and the inner left hand contact of relay 55 to battery.

Relay 50 in operating completes an energizing circuit for relay 52 which can be traced from battery, winding of 52, left alternate contact of relay 50, 231, right normal contacts of relay 55, 229, outer right contacts of relay 61, 228, normal contacts of relay 62, 220, and alternate contacts of relay 44 to ground.

55 Relay 50 also locks itself over its right alternate contact, 230, normal contact of relay 51 and ground on conductor 229 as previously described.

Relay 49 in operating connects ground at 60 its inner left armature contact to conductor 216 thereby causing the operation of relay 53 in a circuit which can be traced over the inner right normal contacts of relay 54, 215, winding of relay 53, conductor 170, and the 65 alternate contact of relay 39 to battery.

Relay 49 also connects to ground at its middle left contact and conductor 222 which extends to the signal control circuit of Fig. 7, thereby setting up a condition as previously described which will cause the transmitting distributor 728 to transmit a single pulse over conductor 727 to the outward end of the trunk to there cause a pulse of negative 120 volt current to be connected to conductor 125 which will cause lamp L to again 75 light, as before described when the called line was plugged into. If the called subscriber should not again release the switchhook lamp L would remain lighted as an indication that the called subscriber has 80 hung up.

After the transmitting distributor 728 has sent out the signal pulse above mentioned a momentary ground is applied to conductor 224 as previously described which causes relay 55 to energize for a sufficient period to permit relay 49 to release which relay was locked under control of relay 55. When relay 49 releases it permits the operation of relay 54 in series with relay 53 by removing the 90 shunt from around relay 54. The energizing circuit of these two relays, 53 and 54, can now be traced from battery, contact of relay 39, 170, winding and alternate contact of relay 53, 214, winding of relay 54, 213, and to ground at the contact of relay 61.

Now, if the subscriber quickly raises his switchhook and depresses it again the following occurs:

When the switchhook is raised supervisory relay 62 operates which in turn releases relay 50 and energizes relay 59, the circuit of which can be traced from battery winding of relay 59, 221, right alternate contacts of relay 52, which relay is slow to release, 105 219, actuated contacts of relay 62, 220 and to ground over contacts of relay 44.

Relays 50 and 52 are slow to release and will hold operated during the flashing interval.

When the switchhook is once more depressed relay 62 deenergizes which again energizes relay 50 which in turn again locks up under control of relay 62.

The release of relay 62 also operates relay 49 which again transmits a pulse of current over the signaling circuit which results in the application of a second pulse of negative 120 volt circuit to conductor 125 which causes relay 10, which was connected to conductor 125 when relay 7 released after the first pulse to operate. Relay 10, due to the connection of its windings, locks up at its left contacts to negative battery, this holding circuit being completed at the alternate contacts of relay 3.

The operation of relay 10 transfers the low resistance circuit for operating relay 1 from steady ground at the normal contact of relay 10 to ground in series with flash-

ing interrupter I, thereby flashing the lamp L, which flashing continues under control of the interrupter until the called subscriber stops working his switchbook.

5 When relay 49 operated at this time, due to the operated condition of relay 54, it caused the operation of relay 51 the circuit of which can be traced from ground, inner left contact of relay 49, 216, inner right alternate contact of relay 54, normal contact and winding of relay 51, 170, and alternate contact of relay 39 to battery.

Relay 51, in operating, locks at its inner left alternate contact under control of relay 61 in an obvious circuit. Relay 51 in attracting its outer left armature transfers the locking circuit of relay 50 from control by relay 62 to relay 61, thereby preventing relay 50 from releasing when relay 62 again 20 operates.

After the completion of the second pulse by transmitting distributor 728 just described, the usual momentary ground is applied to conductor 224 which momentarily 25 energizes relay 55 which causes the release of relay 49.

Due to the slow character of relays 52 and 59, further flashing by the subscriber will not cause these relays to release and, as relay 50 is locked up independent of relay 62, relay 49 cannot be reenergized to cause the transmission of any further signals. With relay 52 operated the release of relay 62 cannot operate relay 61 to cause a signal to be 35 transmitted to the outward end of the trunk to indicate that the receiver of the called subscriber is off the switchhook.

When the called subscriber stops flashing and allows his receiver to remain off the 40 switchhook, relay 62 energizes and remains energized, so long as the receiver is off the switchhook. When relay 52 finally releases ground is connected to the winding of relay 61 and a signal is transmitted over the distributor circuit similar to the signal which 45 indicates that the called subscriber has answered. This signal when received at the outward end of the trunk line releases the flashing relays and extinguishes lamp L 50 thereby indicating that the receiver of the called subscriber is off the switchhook.

The energizing circuit for relay 61 can be traced from battery, outer left normal contact of relay 55, winding of relay 61, 210, 55 outer left normal contacts of relay 49, 211, left alternate contact of relay 54, right normal contacts of relay 52, 219, alternate contacts of relay 62, 220 and contact of relay 44 to ground.

60 If the called subscriber stops flashing and then replaces the receiver on the switchhook then relay 62 releases, which will release relay 59 but relay 52 will remain operated. Under these conditions, ground will be connected to the winding of relay 61 at the

back contacts of relay 59 in the following circuit: ground, normal contacts of relay 59, right alternate contacts of relay 51, 218, left alternate contacts of relay 54, 211, outer left normal contacts of relay 49, winding of relay 61, 234 and contacts of relay 55 to battery. Relay 61 in operating connects ground to leads 222 and 223 thereby causing a signal to be transmitted as before to extinguish lamp L. However as soon as this signal is transmitted due to the momentary operation of relay 55, relays 61, 53, 50 and 54 are released whereupon relay 49 will be energized and a second signal immediately set up and transmitted to the outward position to light 75 lamp L to indicate that the receiver of the called subscriber is on the switchhook.

When the outward operator disconnects from the trunk extending to the line of the called subscriber relay 3 is released. If the 80 called subscriber has replaced his receiver and relay 6 is operated and relays 7 and 4 released then the release of relay 3 closes the circuit of relay 13 as follows: ground, contacts of relay 3, 113, contacts of relay 5, 90 114, contacts of relay 4, 115, contacts of relay 7, winding of relay 13, contacts of relay 8, battery to ground. The operation of relay 13 opens the circuit of relay 5 and connects ground to the signal storing circuit over conductors 120 and 121, causing the disconnect signal to be sent to the outward end of the trunk. This signal is received at the inward end of the trunk circuit as an impulse of positive 120 volt current over conductor 225 which releases relay 39. The release of this relay completes the circuit of relay 63 105 as follows: ground, battery, contacts of relay 39, 240, contacts of relay 63, winding of relay 63, contacts of relay 44 to ground. The operation of relay 63 completes the circuit of lamp Q as follows: ground, battery, contacts of relay 63, 194, contacts of relay 46, 178, lamp Q to ground. Relay 39 also 110 releases 60.

The lighting of this lamp serves to give a disconnect signal to the inward operator. When relay 63 operates, it locks to battery through its own contacts and transfers the winding of relay 46 from battery through the contacts of relay 63 to battery through contacts of relay 39. The operation of relay 63 also opens the busy test lead extending from the tip of the plug to the operator's telephone set.

When the disconnect signal is set up by the signal storing circuit at the outward end and is transmitted to the distant or inward end of the trunk over the distributor signal system, a ground impulse is received from the signal storing circuit over conductor 122, resulting in the operation of relay 8 and the consequent release of relay 13. The release of relay 13 disconnects ground 125 from conductors 120 and 121 and prevents 130

any further signals being transmitted to the signal storing circuit until further changes have been made in the outward trunk circuit.

5 After the inward operator receives the disconnect signal she removes the plug from the jack of the called line causing the release of relay 44 which in turn causes the release of relays 63 and 46, leaving the inward 10 end of the trunk circuit in its normal position to receive another call.

If the inward operator is slow in taking down the connection the outward operator 15 may select the trunk line for another call before the connection for the first call is taken down.

When the outward operator places the plug of the cord circuit into the trunk jack, a signal is transmitted over the signaling 20 circuit which is received at the inward end of the trunk as an impulse of negative 120 volt battery over conductor 225. This impulse causes relay 39 to operate and lock up as previously described. The operation 25 of this relay releases relay 46 and operates relays 60, 41 and 42 and maintains the signal lamp Q lighted.

The circuit operates as previously described and the telephone set of the inward 30 operator Fig. 4 is connected to the trunk line as soon as the operator is free to receive the call whereupon the signal lamp Q is caused to flash as before. The inward operator, however, cannot release her telephone set from the line until she disconnects the trunk line from the subscriber's line by withdrawing the plug from the jack or unless she operates the emergency release key to be later described. This withdrawal releases relay 44 which in turn releases relay 40 63. The release of relay 63 restores the operator's busy test lead to the tip of the plug and connects battery to the winding of relay 46. The inward operator then connects the trunk line to the wanted line and releases her telephone set as previously described.

A release key 700 common to each operator's position is provided to enable the inward operator to release her telephone set from a trunk if desired without requiring her to plug the trunk into an outgoing subscriber's line jack. This circuit is common to all of the trunk circuits to which an operator's telephone set may be connected.

The release key 700 is non-locking and when operated removes ground from conductor 225 and connects ground through the back contacts of relay 77 and the winding 60 of relay 78 over conductor 196 extending to the armature of relay 42. Relay 42 being already energized in a circuit including its right hand winding, a circuit is thus completed through the left hand winding of this 65 relay to battery over the inner right alter-

nate contacts of relay 43, middle normal contacts of relay 47, conductor 172, inner right normal contacts of relay 46, 171, 170 and contacts of relay 39.

Due to the directional connection of the two windings of relay 42 the completion of the circuit through the left hand winding will cause this relay to release. The release of relay 42 disconnects ground from conductor 189 extending to the call sequence circuit thereby causing relay 72 to release. Relay 72 in releasing disconnects ground from conductor 182 thus releasing relay 43 which disconnects the operator's telephone set from the trunk line. The release of relay 42 also disconnects conductor 196 from battery, which was supplied at the left alternate contacts of this relay.

Relay 78 operated in series with the left hand winding of relay 42 but releases when relay 42 releases. When relay 78 operates it connects ground at its contacts to cause the operation of relay 79 which in turn prepares a circuit for the operation of relay 77 which can be traced from battery, winding of relay 79, alternate contacts of relay 79 conductor 197, winding of relay 77, conductor 199 and left hand contacts of release key 700 to ground. Relay 77, however, does not operate at this time as it is shunted by ground at the alternate contacts of relay 78. When relay 78 releases upon the release of relay 42 it removes the ground which previously shunted relay 77 and this relay then operates in the previously described circuit 100 in series with relay 79. The operation of relay 77 removes ground from conductor 196 thus preventing more than one trunk line releasing at once from the operator's telephone set even though the common release key should be held operated. Relays 79 and 77 will be held operated as long as release key 700 is operated.

Delay feature to permit changing cords.

Should the outward operator disconnect before the called subscriber has hung up, for the purpose of changing cords, for example, there will be a delay of about 2½ seconds before the disconnect signal to the inward operator is transmitted, and therefore the trunk will be guarded at the outgoing end for this short interval thus preventing another operator from seizing the trunk during the changing operation. This 115 delay interval is accomplished by means of a series or chain of slow release relays. These relays are common to a group of fifteen trunks.

If the outward operator should reconnect within the 2½ second period the disconnect signal is not sent to the inward operator as relay 3 reoperates before relay 13 operates. This delay in sending a disconnect signal to the inward operator only occurs when relay 130

7 is operated at the time relay 3 is released. When the "A" operator disconnects relay 3 releases which in turn releases relay 4.

With relay 7 operated the release of relays 5 3 and 4 causes the operation of relay 14 the circuit for which can be traced from battery, winding of relay 14, 116, inner right alternate contacts of relay 7, 115, outer left normal contacts of relay 4, outer left alternate contacts of relay 5, 113, and normal contacts of relay 3 to ground.

Relay 13 does not operate to ground conductor 121, thereby sending a signal pulse to the inward end to light the lamp Q as 15 a disconnect signal, until the timing circuit causes ground to be connected to conductor 118, unless the called subscriber should disconnect in the meantime. If this should happen relay 6 operates from negative 120 20 volt current impulse received over conductor 125 causing relay 7 to release. Relay 13 then immediately operates on ground at the normal contacts of relay 3 and causes the disconnect signal to be transmitted as previously described.

The operation of relay 14 completes the circuit of relay 20 over conductor 117. The operation of relay 20 completes the circuit of relay 21 which locks to ground through 30 back contact of relay 24 and front contact of relay 20. The operation of relay 20 also closes the circuit of stepping magnet 22 as follows: ground, contacts of relay 20, 151, contacts of relay 23, 152, winding of magnet 35 22, interrupter contacts of magnet 22, resistance 400, battery to ground. The operation of the switch continues until relay 23 has its circuit completed which is when the wiper associated with the bank contacts O 40 engages ground. This circuit at this time will be as follows: ground, battery winding of relay 23, O, 119, contacts of relay 14, to ground. The operation of relay 23 breaks the circuit of the stepping magnet 22 causing 45 the switch to come to rest with the wipers resting on contacts of the equipment associated with the trunk jack J. The operation of relay 23 completes the circuit of relay 24 as follows: ground, contacts of relay 20, 151, contacts of relay 23, 156, contacts of relay 24, contacts of relay 29, contacts of relay 28, contacts of relay 27, contacts of relay 25, 158, winding of relay 24, battery to ground.

The operation of relay 24 opens the circuit of relay 21. Relay 21 in releasing connects battery to one side of the windings of relays 26, 29, 28, 27 and 25.

The operation of relay 24 causes the circuit of relay 25 to be completed as follows: ground, contacts of relay 20, 151, contacts of relay 23, 156, contacts of relays 24, 157, winding of relay 25, to battery through the contacts of relay 21. The operation of relay 25 opens the circuit of relay 24, but the

circuit of relay 25 remains closed. This combination allows the circuit of relay 27 to be completed as follows: ground, contacts of relay 20, 151, contacts of relay 23, 156, contacts of relay 24, 159, contacts of relay 25, 160, winding of relay 27 to battery through the contacts of relay 21.

The operation of relay 27 opens the circuit of relay 25, allowing it to restore. The operation of relay 27 and the restoration 75 of relay 25 cause the circuit of relay 28 to be closed as follows: ground, contacts of relay 20, 151, contacts of relay 23, 156, contacts of relay 24, 159, contacts of relay 25, contacts of relay 27, 161, winding of relay 80 28, to battery through the contacts of relay 21.

The operation of relay 28, opens the circuit of relay 27, allowing it to restore. The operation of relay 28, and the restoration 85 of relay 27 allows the circuit of relay 29 to be closed as follows: ground, contacts of relay 20, 151, contacts of relay 23, 156, contacts of relay 24, 159, contacts of relay 25, contacts of relay 27, contacts of relay 28, 90 162, winding of relay 29, to battery through the contacts of relay 21.

The operation of relay 29 opens the circuit of relay 28 causing it to restore, the restoration of relay 28 and the operation 95 of relay 29 cause the circuit of relay 26 to be closed as follows: ground, contacts of relay 20, 151, contacts of relay 23, 156, contacts of relay 24, 159, contacts of relay 25, contacts of relay 27, contacts of relay 28, 100 contacts of relay 29, 163, winding of relay 26 to battery through the contacts of relay 21.

At this time the only relays in the timing circuit operated are relays 20, 23 and 26, with this combination the circuit of relay 13 is completed as follows: ground, contacts of relay 20, 151, contacts of relay 23, 156, contacts of relay 24, 159, contacts of relay 25, 27, 28, 29, 164, contacts of relay 110 26, 165, bank contacts N of the switch, 118, contacts of relay 14, 112, winding of relay 13, to battery through the contacts of relay 8.

The operation of relay 13 opens the circuit of relay 5 and the release of this relay opens the circuits of relays 7 and 14. The release of relay 14 removes ground from conductors 117 and 119 causing the release 115 of relays 20, 23 and 26.

In many instances the timing circuit will be released by the trunk circuit before the timing operation is complete. When this happens the circuit restores to normal unless ground is connected to conductors 117 and 119 by some other trunk circuit. In the latter case the switch will hunt for the other circuit and when it is found will start the timing operation over again.

The fact that relay 21 is operated dur-

ing the hunting period insures that any of the relays in the chain which might have been operated at the beginning of the hunting period will release and the full time 5 interval will be obtained in each case.

Call sequence circuit.

The call sequence circuit is arranged to 10 connect an operator's telephone set in successive order to the trunk lines terminating at her position on which calls are waiting.

It is evident that in a group of trunk lines 15 on which calls are originated independently, that call waiting signals may be received at a speed faster than can be handled by the inward operator and that some means is necessary to store up these calls and connect them to the operator's telephone set in regular order.

20 For simplicity, the call sequence circuit, as illustrated, shows relays for three trunks only at one operator's position.

Relays 72, 73 and 74 are operated by 25 ground connected to their windings over conductors individual to the respective trunk lines. The battery for relays 72, 73 and 74 is supplied through the back contacts of relays 76 and 75 arranged in series. The battery supply for relays 72, 73, 74 is furnished through relay 75 which is numerically 30 the highest trunk in the group.

Relays 75 and 76 are operated by ground 35 connections received through the series of relays 72, 73 and 74 of numerically lower trunks.

For the purpose of illustration we will assume that calls are originated simultaneously on trunks, 1, 2 and 15. Under these 40 conditions there will be a ground placed on each 189 conductor extending from trunks 1, 2 and 15. These ground connections operate relays 72, 73 and 74. The operation of relay 72 connects ground over conductor 182 to number 1 trunk circuit, but the operation of relays 73 and 74 at this time does not change the circuit conditions so long as relay 72 is operated. The operation 45 of relay 72 completes the circuit of relay 43 as follows: ground, contacts of relay 71, contacts of relay 72, conductor 182, winding of relay 43, battery to ground. The operation 50 of relay 43 connects the operator's telephone set to trunk number 1.

When relay 72 is released which will be 55 after the operator at the inward position completes the connection then relay 76 is operated over the following path: ground, contacts of relay 71, contacts of relay 72, contacts of relay 73, winding of relay 76, battery to ground. The operation 60 of relay 76 completes the circuit of relay 43 of No. 2 trunk and connects the operator's telephone set to that particular trunk.

65 After the connection has been established over No. 2 trunk, relay 73 is released there-

by allowing the operation of relay 75 by the following path: ground, contacts of relay 71, contacts of relay 72, contacts of relay 73, contacts of relay 74, 186, winding of relay 75, battery to ground. The operation 70 of relay 75 completes the circuit of relay 43 of trunk No. 15, thereby connecting the operator's telephone set to that trunk.

After the establishment of the connection 75 the operator's telephone set is disconnected from trunk No. 15.

The operation of relay 75 which is the highest numbered trunk of this series breaks the battery supply extending to the windings of all the relays 72, 73, 74, etc., in the 80 series. This prevents their operation in case a call should originate on one or more of the other lower numbered trunks in the group. When a connection has been established between the trunk and the called line, 85 or the release key 700 is operated, as previously described, ground is removed from conductor 189 and this releases relay 74, which in turn releases relay 75.

Relays 72, 73 and 74 are slow to release 90 their armatures and consequently there is an interval of time between the release of each relay from 72, 73, 74, etc., to its respective relay 76, 75, etc. By means of this 95 time interval the call sequence circuit is made to operate in the regular order from the first toward the last trunk until all the signals of the higher numbered trunk lines have been transmitted. After this the sequence circuit returns to its normal starting 100 position and is ready to repeat the operation.

Emergency transfer circuit.

The emergency transfer circuit is common 105 to all of the inward trunks terminating at one inward operator's position. This circuit allows the inward operator to answer manually on the trunk lines terminating at her position by operating the team key X associated with each trunk. This feature will be necessary in case of trouble in the call sequence circuit. This circuit is operated by means of the emergency transfer key 110 729 which, when operated, connects ground to the windings of relays 70 and 80. The operation of relay 70 disconnects ground from conductor 190 thereby preventing operation of the call sequence circuit and opens 115 the conductor 257 extending to the call sequence circuit at the adjacent position and also transfers conductor 211 from the position release key at the adjacent position to the one at the home position. The operation 120 of this relay also transfers conductor 251 extending to interrupted battery at peremptory frequency to one corresponding to a busy back frequency.

125 The operation of relay 80 transfers conductors 142, 143 and 254 common to the 130

toll line from conductors extending to the adjacent operator's telephone set and connects them to the home position telephone set.

5. What is claimed is:

1. In a telephone exchange system a trunk line terminating at an operator's position, a signal at said position associated with said trunk line, means for displaying said signal and for connecting said telephone set to the trunk when connection is made with the trunk jack by means of one of said cord circuits, means operated when the plug is placed into the jack of subscriber's line for restoring the signal and for disconnecting said operator's telephone set, means for causing the re-operation of the signal when the "A" operator disconnects said one cord circuit from the trunk jack and means for maintaining said signal operated and for connecting said operator's telephone to said trunk in case said "A" operator again connects a cord circuit therewith before the "B" operator disconnects the trunk plug from the jack of the subscriber's line.
- 10 to indicate the seizure of said trunk line at its outward end, a telephone set at said operator's position and means for automatically connecting said telephone set to said trunk line when said trunk is seized, means for automatically retiring said signal and for disconnecting said telephone set when said calling trunk is connected to a called line, means for re-displaying said signal when said trunk line is released at its outward end and means for maintaining the display of said signal and for re-connecting said telephone set when said trunk line is again seized at the outward end before it is disconnected from said called line.
- 15 2. In a telephone exchange system, the combination of an "A" operator's position and a "B" operator's position, trunk lines extending between said positions, means at the "B" operator's position for connecting said trunks to outgoing lines, a plurality of connecting circuits at the "A" operator's position for connection with said trunk lines, an individual signal for each of said trunk lines and an operator's telephone set associated with said trunk lines at the "B" operator's position, a signalling circuit common to said trunks extending between said positions, means controlled over said common signalling circuit when a connection is made with one of said trunks at the "A" operator's position for causing the operation of the signal and for connecting the operator's telephone set to said trunk, means controlled at the "B" operator's position for disconnecting the signal and for disconnecting the operator's telephone set from said trunk, when the trunk is connected to said outgoing line, means controlled from the "A" operator's position when said first connection is broken thereat and a second connection is made with said trunk before a disconnection is made at the "B" operator's position for again operating said signal and for re-connecting the operator's telephone set to said trunk.
- 20 3. In a telephone exchange system, the combination of an "A" operator's position, a "B" operator's position, a trunk line extending between said positions and terminating at the "A" operator's position in a trunk jack and at the "B" operator's position in a plug, a subscriber's line at the "B" operator's position terminating in a jack for connection with said plug, an operator's telephone set at said "B" position, a signal asso-
- 25 ciated with said plug, a plurality of cord circuits at the "A" operator's position arranged to be connected with said trunk jack, means for causing the operation of said signal and for connecting said telephone set to the trunk when connection is made with the trunk jack by means of one of said cord circuits, means operated when the plug is placed into the jack of subscriber's line for restoring the signal and for disconnecting said operator's telephone set, means for causing the re-operation of the signal when the "A" operator disconnects said one cord circuit from the trunk jack and means for maintaining said signal operated and for connecting said operator's telephone to said trunk in case said "A" operator again connects a cord circuit therewith before the "B" operator disconnects the trunk plug from the jack of the subscriber's line.
- 30 4. In a telephone exchange system, the combination of an "A" operator's position, a "B" operator's position, trunk lines extending between said positions, means at the "B" operator's position for connecting said trunks to outgoing lines, a plurality of connecting circuits at the "A" operator's position for connection with said trunk lines, an individual signal for each of said trunk lines and an operator's telephone set associated with said trunk lines at the "B" operator's position, a signalling circuit common to said trunks extending between said positions, means controlled over said common signalling circuit when a connection is made with one of said trunks at the "A" operator's position for causing the operation of the signal and for connecting the operator's telephone set to said trunk, means controlled at the "B" operator's position for disconnecting the signal and for disconnecting the operator's telephone set from said trunk, when the trunk is connected to said outgoing line, means controlled from the "A" operator's position when said first connection is broken thereat and a second connection is made with said trunk before a disconnection is made at the "B" operator's position for again operating said signal and for re-connecting the operator's telephone set to said trunk.
- 35 5. In a telephone exchange system, the combination of an "A" operator's position and a "B" operator's position, trunk lines extending between said positions, an individual signal for each of said trunk lines and a telephone set at the "B" operator's position, means at the "B" operator's position for connecting said trunks to outgoing lines, a signalling circuit common to said trunks extending between said positions, means for transmitting a signal over said common signalling circuit from the "A" to the "B" operator's position for causing the operation of one of said signals and for connecting the telephone set to said trunk, when one of said trunk
- 40
- 45
- 50
- 55
- 60
- 65

lines is seized at said "A" position, means for transmitting a second signal over said common signalling circuit for again operating said signal when said trunk is released 5 at said "A" position and means for transmitting a third signal over said common circuit for maintaining said signal operated and for re-connecting the operator's telephone set to said trunk in case said trunk is 10 re-seized at said "A" operator's position before disconnection is effected at said "B" position.

6. In a telephone exchange system, the combination of an "A" operator's position 15 and a "B" operator's position, trunk lines extending between said positions, means at each of said positions for effecting connections with said trunk lines, an individual signal for each of said trunk lines and 20 an operator's telephone set associated with said trunk lines at said "B" position, a signalling circuit common to said trunks extending between said positions, means controlled over said signalling circuit for 25 causing the operation of one of said signals and the connection of the operator's telephone set to said trunk line when a connection is effected with one of said trunks at the "A" operator's position, means at 30 the "B" operator's position for effacing said signal and disconnecting said operator's telephone set when a connection is effected at said "B" operator's position, means at said "A" operator's position for causing the re- 35 operation of said signal over said common signalling circuit when said connection at the "A" position is released and means controlled over said signaling circuit when a second connection is made with said trunk 40 line at the "A" operator's position before a disconnection is made at the "B" operator's position for maintaining the operation of said signal and for re-connecting the telephone set to the trunk.

45 7. In a telephone exchange system, the combination of an "A" operator's position and a "B" operator's position, trunk lines extending between said positions, means at each of said positions for making connections with said trunk lines, an operator's telephone set and an individual signal for each of said trunk lines associated with the trunk lines at the "B" operator's position, a relay individual to each said trunk line at the "B" operator's position, a signalling circuit common to said trunks extending between said positions, means controlled over 50 said common signalling circuit when a connection is made at the "A" operator's position with one of said trunk lines for operating said relay to cause the operation of said signal and to cause the connection of the operator's telephone set to one of said trunk lines, means at the "B" operator's position 55 for making a connection with said trunk

line, means responsive to such connection at the "B" position for effacing said signal and for disconnecting the operator's telephone set from said trunk line, means responsive to disconnection at said "A" position for releasing said relay and reoperating said signal and means responsive to the re-operation of said relay upon another connection being effected with said trunk at the "A" position before said trunk is disconnected at said "B" 75 position for maintaining the operated condition of said signal and for reconnecting said telephone set with said trunk.

8. In a telephone exchange system, the combination of a circuit having an outgoing 80 and an incoming end, means at each end of said circuit for effecting connections therewith a signal at the incoming end of said trunk circuit, means controlled at the outgoing end of said circuit when a connection 85 is effected therewith for causing the operation of said signal, means at the inward end of said circuit, when a connection is effected at the said inward end of said circuit, for effacing said signal, means for causing the 90 re-operation of said signal a second time when said circuit is disconnected at the outward end and means responsive to a re-connection at the outward end before disconnection 95 is effected at the inward end of maintaining the operated condition of said signal.

9. In a telephone exchange system, the combination of a trunk circuit having an outgoing and an incoming end, means at 100 each end of said circuit for effecting connections therewith a signal and a telephone set at the incoming end of said circuit, means controlled at the outgoing end of said trunk circuit when a connection is effected therewith for causing the operation of said signal in a steady manner and the connection of the telephone set with said circuit, means controlled at the inward end of said circuit for effacing said signal and disconnecting 105 said telephone set when a connection is effected at the said inward end of said circuit, means for causing the reoperation of said signal in said steady manner when said trunk is disconnected at said outgoing end and means for maintaining the operation of 110 said signal, upon the reconnection of said telephone set to said trunk and a subsequent flashing of said signal when a second connection is effected at said outgoing end before disconnection takes place at said incoming end.

10. In a telephone exchange system, a trunk line terminating at one end in an outward operator's position and at the other end in an inward operator's position, a signal lamp associated with said trunk at said inward position, operator controlled means for seizing said trunk line at said outward position, means for extending said trunk to another line at said inward position, auto- 115 120 125 130

matic means for lighting said lamp when said trunk is seized at the outward position, automatic means for extinguishing said lamp when said trunk is extended at the inward position, automatic means for relighting said lamp when said outward end of the trunk is released, and, automatic means for maintaining said lamp lighted when said trunk is seized at said outward position a second time before said extension at the inward position has been released.

11. In a telephone exchange system, a line signal displayed at the incoming end of a trunk line to indicate the seizure thereof at the outgoing end, means for effacing said

signal in response to the connection of said trunk, at its incoming end, with an extension line, means for re-displaying said signal upon the release of said trunk at the outgoing end and means for maintaining the display of said signal upon the seizure, a second time, of said trunk at the outgoing end before it is disconnected at said incoming end.

In witness whereof, we hereunto subscribe our names this 7th and 8th day of October A. D., 1924.

KARL M. FETZER.
NORMAN A. NEWELL.
